UNITED STATES PATENT OFFICE.

CARNIE B. CARTER AND ALBERT E. COXE, OF PITTSBURGH, PENNSYLVANIA,
ASSIGNORS, BY MESNE ASSIGNMENTS, TO S. KARPEN & BROS., A CORPORA-
TION OF WEST VIRGINIA.

METHOD OF PRODUCING ACTIVE METHYLENE BODIES.

1,423,753.

Specification of Letters Patent. Patented July 25, 1922.

No Drawing.

Application filed August 27, 1920. Serial No. 406,435.

To all whom it may concern:

Be it known that we, CARNIE B. CARTER and ALBERT E. COXE, citizens of the United States, residing at Pittsburgh, in the county of Allegheny and State of Pennsylvania, have invented a new and useful Improvement in Methods of Producing Active Methylene Bodies, of which the following is a specification.

10 This invention relates particularly to a process of producing active methylene bodies, that is, active bodies containing the methylene radical (CH_2), particularly formaldehyde (CH_2O) and hexamethylenetetramine [$(\text{CH}_2)_6\text{N}_4$].

A known method of producing hexamethylenetetramine is to pass ammonia through formaldehyde. The usual method of producing formaldehyde is to pass wood alcohol over a catalyst. This method is becoming inadequate and expensive, owing to the increasing difficulty of obtaining wood alcohol in sufficient quantity.

According to the present process ozone (O_3), or an ozonized agent, such as ozonized air or ozonized oxygen, is combined with ethylene gas (C_2H_4) under conditions favoring the immediate or continuous conversion of the ethylene ozonide ($\text{C}_2\text{H}_4\text{O}_3$), which 25 these bodies combine to form, into constituents, of which the main or predominating one is formaldehyde. Thus, the formation of any considerable amount of ethylene ozonide, which is of an explosive nature, is 30 obviated, and a large yield of formaldehyde is obtained. The formaldehyde may be recovered as such, or it may be combined with ammonia to form hexamethylenetetramine and this body may be separated from the 35 other substances formed.

Ethylene will combine readily with ozone to form ethylene ozonide, and this tends to split up into formic acid (CHOOH) and formaldehyde, the formic acid largely predominating, however.

The primary object of the present process is to control the reactions in such manner as to produce a large yield of the active methylene body and reduce the yield of formic acid to a minimum. This, as indicated, is 50 accomplished without the formation of any considerable quantity of ethylene ozonide, or, rather, the ethylene ozonide, if it forms in the process, is continuously converted, as

formed, into constituents, the main one of which can be recovered as an active methylene body.

The agent or medium which it is preferred to employ to prevent the formation of a preponderant proportion of formic acid 60 is water, and this is preferably employed in the form of steam.

The preferred method of procedure is as follows:

Introduce ethylene, steam and an ozonized 65 agent, such as ozonized air, into a drum, where an intimate and free commingling of these substances may take place. The introduction may be accomplished, for example, by passing ethylene gas and steam through 70 pipes which communicate with a third pipe through which the ozonized air passes to the drum. The junction of the ethylene pipe and steam pipe with the ozonized air-pipe may be near the point where the latter com- 75 municates with the drum.

If desired, however, each of the three 80 pipes may lead directly to the drum. The purpose is to have the ozonized air combine with the ethylene in the presence of water, as water acts as an agent favoring the production of an increased yield of the active methylene body and a diminished yield of formic acid. Apparently, reactions 85 occur in accordance with the following formulæ:

As stated, it is preferred to have the water 90 present in the form of steam or water-vapor, which favors the free commingling of the substances entering into the reaction; and the reaction is favored by an elevated temperature, that is, a temperature above ordinary room temperatures. For example, if steam, ethylene and ozonized air be passed into a drum or large vessel, the steam being at or near the boiling point of water, the result will be to maintain the temperature where the gases and water-vapor or steam commingle at a temperature near the boiling point of water. Under such conditions, one may obtain a yield of 70 per cent or 105 more of formaldehyde and 15 per cent or less of formic acid. The fine subdivision of the water at the elevated temperature seems 100

to favor a larger yield of formaldehyde. The yield will vary according to conditions. If desired, the steam may be superheated which favors a larger yield of formaldehyde. The proportions in which the substances may be commingled is sufficiently indicated by the formulae. It may be added, however, that a large excess of steam seems to favorably influence the result. It seems desirable that the commingling of the gases shall take place in a large drum containing no internal obstructions, such as baffle-plates.

To effect the separation of the substances yielded by the reactions, one may proceed as follows:

Pass the gases from the drum into a scrubber containing water, and thus cause the gases to be absorbed by the water; then run the saturated water into a tank and neutralize with an alkali, such as potassium hydrate, sodium hydrate, ammonium hydrate, or calcium hydrate. After neutralization, which fixes the formic acid as a formate, the methylene body may be recovered as hexamethylenetetramine by the following steps:

Introduce into the neutralized solution a solution of ammonium hydrate, and thus change the formaldehyde into hexamethylenetetramine; evaporate the slightly ammoniacal solution to a thick syrup, or dryness, preferably under a vacuum. Then boil the residue in carbontetrachloride (CCl_4) or other solvent for hexamethylenetetramine, which is not a solvent for the formates; withdraw the solution while hot, allow to cool and the hexamethylenetetramine will crystallize out; then dry the hexamethylenetetramine, if desired.

The formic acid remains fixed in the first residue. The hydrogen peroxide (H_2O_2) apparently largely disappears or wholly disappears in the process.

If it be desired to recover the formaldehyde as such, the saturated solution from the scrubber may be neutralized with a non-volatile alkali, such as lime or caustic soda; the solution may then be evaporated to dryness, a percentage of the formaldehyde passing over and being collected. The heating may be continued at a temperature above 100° C. to evaporate any polymerized formaldehyde, and this may be collected. The formate remains as a residue. The distillate is a dilute solution of formaldehyde. This may be concentrated by known methods, if desired.

Various modifications of the process for effecting the union of ethylene and ozone in the presence of water or water-vapor, so that water may also enter into the reaction, may also be practiced. For example, one may pass ethylene and ozone into a scrubbing machine containing water, preferably heated to near the boiling temperature. Again, one may pass ethylene and ozone into a tower

filled with broken glass or porcelain, over which hot water trickles. Still, another modification is to mix ethylene and ozone in a chamber having walls which are wetted or maintained in a wetted condition.

It may be stated that ethylene may be obtained in abundance from grain alcohol in a well-known manner. It may, if desired, be produced as required for the present process and passed directly to the point where it is to be mixed with the ozonized agent and steam.

As indicated above, the employment of a large hydrolyzing vessel, or drum, without internal obstructions therein, seems to favor a larger yield of formaldehyde; also the superheating of the steam affords an increased yield of formaldehyde.

The foregoing detailed description has been given for clearness of understanding only, and no unnecessary limitations should be understood therefrom, but the appended claims should be construed as broadly as permissible, in view of the prior art.

What we regard as new, and desire to secure by Letters Patent, is—

1. The method of producing an active methylene body which comprises reacting upon ethylene with an ozonized agent in the presence of an aqueous medium adapted to favor the formation of a preponderant proportion of the active methylene body.

2. The method of producing an active methylene body which comprises reacting upon ethylene with an ozonized agent in the presence of H_2O .

3. The method of producing an active methylene body which comprises reacting upon ethylene with an ozonized agent in the presence of an aqueous medium adapted to favor the production of a preponderant proportion of formaldehyde, then absorbing in water the gases produced, and then separating the methylene body from the other constituents.

4. The method of producing an active methylene body which comprises reacting upon ethylene with an ozonized agent in the presence of H_2O , then absorbing in water the gases produced, and then separating the methylene body from the other compounds.

5. The method of producing an active methylene body which comprises reacting upon ethylene with an ozonized agent in the presence of an aqueous medium adapted to prevent the formation of a preponderant proportion of formic acid, then absorbing in water the gases produced, neutralizing the solution, and then effecting the separation of the methylene substance from the formates.

6. The method of producing an active methylene body which comprises reacting upon ethylene with an ozonized agent in the presence of H_2O , then absorbing in water the gases produced, neutralizing the solu-

tion, and then effecting the separation of the methylene substance from the formates.

7. The method of producing an active methylene body which comprises reacting 5 upon ethylene with an ozonized agent in the presence of steam.

8. The method of producing an active methylene body which comprises commingling ethylene and an ozonized agent with 10 water-vapor at elevated temperature.

9. The method of producing an active methylene body which comprises commingling ethylene, superheated steam and an ozonized agent.

15 10. The method of producing an active

methylene body which comprises commingling ethylene, water-vapor and an ozonized agent in a large vessel substantially free from internal obstructions.

11. The method of producing formaldehyde which comprises combining ethylene and an ozonized agent in the presence of H_2O , absorbing in water the gases formed by the reactions, neutralizing the solution with a non-volatile alkali, evaporating the solution, thus leaving the formic acid fixed as a formate, and recovering the formaldehyde from the distillate. 20 25
